UNITED STATES PATENT OFFICE.

HOWARD A. WARFEL, OF YORKTOWN, INDIANA.

MIXING APPARATUS.

Application filed August 16, 1921. Serial No. 492,657.

To all whom it may concern:

Be it known that I, HOWARD A. WARFEL, a citizen of the United States, residing at Yorktown, in the county of Delaware and State of Indiana, have invented certain new and useful Improvements in Mixing Apparatus, of which the following is a specification.

This invention relates to apparatus for mixing food materials and beverages on the order of malted milk and the like.

Particular objects of the invention are to provide practical and efficient mechanism for mixing either one or a number of drinks or other concoctions, as may be required, and further, to make the apparatus in convenient attractive form and quiet in operation.

The various novel features by which these objects are attained will become apparent from the following specification which is to be read in conjunction with the drawings accompanying and forming part of the same and which disclose the invention embodied in but one of its possible commercial forms.

Figure 1 in the drawings referred to is a side view of the mixing apparatus with the base portion of the device shown in section to illustrate the driving gearing and switch operating mechanism.

Figure 2 is a bottom plan view of the apparatus.

Figures 3 and 4 are broken enlarged sectional views showing one of the mixers in the up-raised, inactive and lowered, operative positions respectively.

Figure 5 is a detached perspective view of one of the glass holders.

Figure 6 is a broken side elevation of the latch release.

Figure 7 is a broken plan view of the same.

Figure 8 is a horizontal sectional view of this mechanism as taken on substantially the plane of line 8-8 of Figure 6.

Figure 9 is a broken sectional view of the stationary section of one of the columns and the switch operating mechanism associated therewith.

Figures 10 and 11 are horizontal sectional views of the switch operating cam mechanism taken on substantially the plane of line 10-11 of Figure 9.

In the machine illustrated, there are four mixers, any one or all of which are operable at will from a single driving motor.

These mixers are shown in Figure 1 as mounted in a row on a suitable supporting base 15 which is hollow to form a housing for the gearing and switch mechanism, the motor 16 being supported on this base at one end of the row of mixers.

These mixers, as more clearly shown in Figures 3 and 4 consist in each instance of a tubular column 17 carried by a flanged bushing 18 having a squared hub 19 seated in a correspondingly shaped opening in the top of the base, said fixed column having an oversliding tubular extension 20 carrying the mixing element 21 and a disconnectable part of the gearing for actuating the same.

The telescopic column section 20 is shown as non-rotatably guided on the fixed column section by having a part 22 slidably fitting over an upstanding guide rod or post 23, which has a head 24 at its upper end to limit the retractive upward movement of the movable column section.

The mixing element is shown as carried by a spindle 25 having a screw-threaded connection at 26 with the vertical shaft section 27 journaled in the head 28 of the movable column section and connected by bevel gearing 29 with one end of a horizontal shaft 30, whose opposite end is connected by bevel gearing 31 with a vertical shaft section 32 journaled in a bearing 33 carried by the sliding column section.

The sliding column section is thrust upward by a spring 34 interposed between the shoulder provided by the bearing 33 at the top of the sliding column section and the shoulder provided by the bearing 35 in the upper end of the fixed column section. In this latter bearing there is journaled an upright shaft 36 of tubular construction to receive the lower end of the upper shaft section 32 which may be pointed as indicated at 37 to facilitate its entrance into the end of the tubular shaft and which carries a clutch disc 38 slidably keyed thereon at 39 and adapted to be coupled with a corresponding clutch element 40 on the upper end of the tubular shaft. The clutched engagement of these two shaft sections is illustrated in Figure 4, wherein it will be seen that the upper shaft section 32 telescopes into the lower tubular shaft section 36 and that the sliding clutch disc 38 engages with the clutch member 40 to afford a driving connection between these parts. The clutch

disc 39, may be acted on by a spring which will yieldingly hold it engaged with the driving element 40, the end of the key way at 39 in the shaft forming a stop to limit the extent of sliding movement of the disc.

The drive shafts 36 in the illustration are provided with pulleys 41 at their lower ends, within the hollow base, over which runs a driving belt 42, said belt also passing over 10 a pulley 43 carried by pulley 44 which is connected by belt 45 with pulley 46 on the lower end of the motor shaft 47. The belt 42 which forms the common drive for all four spindles may be held under proper 15 tension as by means of a spring actuated belt-tightening idler 48.

According to my present disclosure, the motor is automatically cut into circuit each time any one of the mixing heads is lowered, 20 this being accomplished through the instrumentality of cam-like members 49 projecting through slots 50 in the fixed column sections into position to be engaged and forced back by the oversliding column sections, said 25 cam members being affixed to the upper ends of upright control rods 51 within the columns and which carry at their lower ends arms 52 in engagement with lugs 53 on the longitudinally shiftable switch actuating 30 rod 54.

This latter rod is shown in Figure 2 as normally forced to the left by a spring 55 and as having an arm or extension 56 carrying a contact 57 adapted to bridge the contact springs 58. The switch thus provided 35 is interposed in the motor circuit and consequently the motor is under the direct control of each and all of the mixing devices.

Some means are preferably provided for 40 retaining the mixing devices in their lowered operative positions. I have shown for this purpose, a hook or dog 59 pivotally supported at 60 in each of the fixed column sections and arranged to project through an 45 opening 61 into holding engagement in the opening 62 in the sliding column section, as shown in Figure 4. These holding dogs are 50 shown as thrust outwardly by springs 63 so that they will automatically snap into holding engagement with the sliding column sections when the same are lowered to bring the mixers into operation.

To release the hold-down latches, I have 55 shown each mixer head as provided with a handle 64 having a stem 65 journaled in a bearing 66 at the side of the head and carrying at its lower end, an angularly extending arm 67 arranged in the depressed position of the head to overlie the point of the latching dog.

The glasses or other containers are located 60 and held in position beneath the mixers by positioning devices shown in the form of spring-yokes 68 having curved arms to receive and partially embrace the glasses, said

yokes being set in slots 69 cut in the upper ends of the posts 70 which having squared lower ends 71 seated in correspondingly shaped sockets in the top of the base and split as indicated at 72 to form spring 70 tongues frictionally engaging in such seats. This construction causes the glass holders to be firmly held in place and yet enables their ready removal for cleaning or other purposes. This detachability is particularly important where it may be desired to operate on material which may be within a bowl or relatively large container.

In the ordinary use of the invention, the glass or glasses containing the ingredients 80 are slipped into place in the glass holders and the mixer heads are depressed to lower the mixing elements down into the material in the glasses. As the first mixer is depressed and the upper column section thereof rides over the cam 49, the switch will be thrown and the motor started in operation. In the continued lowering movement and after the mixing element has been lowered 85 fully into the glass, the upper shaft section 90 will enter the lower tubular shaft section and the two will become clutched together, resulting in the driving of the mixing element. It will be evident that the mixing 95 heads may be operated in sequence or simultaneously, the effect in either instance being practically the same. The mixing devices being automatically latched in their depressed condition, remain in operation until the operator actuates the handles 64 which, 100 as before described, serve to release the hold-down latches. When these latches are released, the mixer heads are automatically raised by the retracting springs 34. In this 105 lifting movement, the driving connections are automatically uncoupled and this uncoupling is effected at a time before the mixing element is lifted clear of the glass. Hence the mixing element is in an idle or 110 non-rotating condition when it is lifted out of the glass.

This prevents scattering the material as the mixers are withdrawn. If only one mixing device is in operation, the switch restoring spring 55 will operate to cut out the motor as soon as the movable section of the column slides free of the switch operating cam 49, but the motor will not be cut out of circuit until all the mixers have been withdrawn.

What I claim is:

1. In apparatus of the character disclosed, a plurality of tubular columns, each of said columns having a movable telescopic section, mixing elements and driving connections therefor carried within said movable column sections, driving means within the relatively fixed sections of the columns engageable with and disengageable from the driving connections in the movable column sections and 125 130

common operating means for said driving means in the several columns.

2. In apparatus of the character disclosed, a plurality of tubular columns, each of said 5 columns having a movable telescopic section, mixing elements carried by said movable column sections, driving connections for the mixing elements housed within the movable column sections, driving means within 10 the relatively fixed sections of the columns engageable with and disengageable from the driving connections in the movable column sections, common operating means for said driving means in the several columns and independent controllers for said driving means 15 operable by the movable sections of the several columns.

3. In apparatus of the character disclosed, a plurality of columns having vertically movable 20 sections, stirring elements carried by said vertically movable sections, driving means therefor housed within and connectable and disconnectable in the vertical movements of said movable sections, a motor for 25 operating said driving means and controlling mechanism for said motor independently operable by each of the movable column sections.

4. In apparatus of the character disclosed, 30 a supporting base, a row of mixer columns mounted on said base, a motor supported on the base, drive shafts in the mixer columns, a common drive shaft extending from the motor to said drive shafts located at the 35 under side of the base, said columns having extensible sections, mixing elements carried by said extensible sections, driving connections for the mixing elements housed within the extensible sections and detachable 40 couplings between said driving connections and the drive shafts aforesaid.

5. In apparatus of the character disclosed, 45 a supporting base, a row of mixer columns mounted on said base, a motor supported on the base, drive shafts in the mixer columns, gearing from the motor to said drive shafts located at the under side of the base, said 50 columns having extensible sections, mixing elements and driving connections therefor carried by said extensible sections, detachable 55 couplings between said driving connections and the drive shafts aforesaid, and means for releasably securing the extensible column sections with the driving connections operably coupled with the drive shafts.

6. In apparatus of the character disclosed, 60 a supporting base, a row of mixer columns mounted on said base, a motor supported on the base, drive shafts in the mixer columns, gearing from the motor to said drive shafts located at the under side of the base, said 65 columns having extensible sections, mixing elements and driving connections therefor carried by said extensible sections, detachable 70 couplings between said driving connec-

tions and the drive shafts aforesaid and control mechanism for the motor operable by the extensible column sections.

7. In apparatus of the character disclosed, 75 a hollow base, a plurality of independently operable mixing devices mounted on said base, a motor mounted on the base, a common drive shaft within the hollow base, extending from the motor and intergeared to the several mixing devices and a controlling 80 switch for the motor also mounted in said hollow base.

8. In apparatus of the character disclosed, 85 a hollow base, a plurality of independently operable mixing devices mounted on said base, a motor mounted on the base, a common drive shaft within the hollow base extending from the motor and intergeared to the several mixing devices, a controlling switch for the motor also mounted in said hollow base 90 and operating means for said controlling switch under control of the individual mixing devices.

9. In an apparatus of the character disclosed, 95 a hollow base, a plurality of independently operable mixing devices mounted on said base and extending downwardly toward said base, a motor mounted on the base, a common drive means within the hollow base extending from the motor and connected to the several mixing devices.

10. In apparatus of the character disclosed, 100 a tubular column comprising relatively fixed and telescopic sections, discon- 105 nectable drive gearing housed within said relatively fixed and movable column sections, a mixing device carried by the movable column section and operable by the gearing carried thereby and means for releasably securing the column sections with the discon- nectable gearing in coupled relation.

11. In apparatus of the character disclosed, 110 a tubular column comprising relatively fixed and telescopic sections, discon- 115 nectable drive gearing housed within said relatively fixed and movable column sections, a mixing device carried by the movable column section and operable by the gearing carried thereby, means for releasably securing the column sections with the discon- nectable gearing in coupled relation and comprising a holding latch on one of the column sections arranged to engage a shoulder on the companion column section and means for releasing said latch from its holding engagement with said shoulder.

12. In apparatus of the character disclosed, 125 a tubular column comprising relatively fixed and telescopic sections, discon- 130 nectable drive gearing in said relatively fixed and movable column sections, a mixing device carried by the movable column section and operable by the gearing carried thereby, means for releasably securing the column sections with the

disconnectable gearing in coupled relation and comprising a holding latch on one of the column sections arranged to engage a shoulder on the companion column section 5 and means for releasing said latch from its holding engagement with said shoulder and including a retracting finger carried by said companion column section and arranged to overstand said latch when the column sections 10 are in the latched relation.

13. In apparatus of the character disclosed, telescopic column sections, disconnectable gearing carried within said sections, a latch for securing the sections in 15 position with said gearing in coupled relation, a spring for relatively shifting the telescopic sections to uncouple said gearing, means for releasing the latch and a mixing element carried by one of the column sections 20 and operably connected with the gearing carried thereby.

14. In apparatus of the character disclosed, a base, a tubular column mounted thereon and comprising a fixed section and 25 a sliding section, means for guiding the sliding section non-rotatably over the fixed section, a latch in the fixed section for releasably securing the sliding section in predetermined relation, a spring within the 30 sliding section for relatively separating said sections, a drive shaft journaled in the fixed section, a driven shaft within the sliding section, cooperating clutch elements on said drive and driven shafts and a mixing element carried by the sliding section and connected with the driven shaft.

15. In apparatus of the character disclosed, a base, a tubular column mounted thereon and comprising a fixed section and 40 a sliding section, means for guiding the sliding section non-rotatably over the fixed section, a latch in the fixed section for releasably securing the sliding section in predetermined relation, a spring within the sliding section for relatively separating said sections, a drive shaft journaled in the fixed section, a driven shaft within the sliding section, cooperating clutch elements on said drive and driven shafts and a mixing element carried by the sliding section and connected with the driven shaft.

terminated relation, a spring within the sliding section for relatively separating 45 said sections, a drive shaft journaled in the fixed section, a driven shaft within the sliding section, cooperating clutch sections on said drive and driven shafts, a mixing element carried by the sliding section and connected with the driven shaft, a cam element projecting through an opening in the fixed column section into position to be engaged by the sliding column section, 50 a switch operated by said cam element and a motor for the drive shaft under control of said switch.

16. In apparatus of the character disclosed, a vertically movable head, a stirring device carried by said head and gearing housed within the head for operating said stirring device, including a coupling releasable and engageable at a point adjacent the uppermost limit of travel in the vertical 55 movements of said head.

17. In apparatus of the character disclosed, a vertically movable head, a stirring device carried by said head and gearing housed within the head for operating said stirring device, including a coupling releasable and engageable at a point adjacent the uppermost limit of travel in the vertical movements of said head, said coupling being engageable just after the head has been lowered sufficiently to enter the stirring device in a glass or tumbler of predetermined size and being releasable just before the head has lifted far enough to remove the stirring device from a glass or tumbler of such predetermined size.

In testimony whereof I affix my signature in presence of two witnesses.

HOWARD A. WARFEL.
